[57] **CLAIM**

The ornamental design for a semi-conductor element with terminal casing, as shown.

DESCRIPTION

FIG. 1 is a perspective view of the front, top and right side of a semi-conductor element with terminal casing showing our new design;

FIG. 2 is a front elevational view thereof;

FIG. 3 is a top plan view thereof;

FIG. 4 is a right side elevational view thereof;

FIG. 5 is a left side elevational view thereof;

FIG. 6 is a rear elevational view thereof; and,

FIG. 7 is a bottom plan view thereof.

*FIG. 1**FIG. 2**FIG. 3*FIG. 4

FIG. 5

FIG. 6

FIG. 7
